WINDOW STRUCTURES

Rupert L. Evans and John P. Malmrose, Kewanee, Ill., assignors to Kewanee Manufacturing Company, a corporation of Illinois

Filed Dec. 6, 1957, Ser. No. 701,213

3 Claims. (Cl. 189—1)

This invention relates to window structures and particularly to basement windows of the window-well type.

With well-type basement windows it is usual to cast the window frame into the concrete basement wall completely or partially below the ultimate outside grade level, and then, after stripping of the forms from the wall, to secure an arcuate well-forming wall of sheet metal in a spanning relation to the window opening by fastening elements extended through the ends of the well structure into the wall near opposite vertical edges of the window opening. These fastening operations have been performed according to different conventional methods as by expanding anchor studs or by use of a stud gun, and this has not only been costly but has required the employment of two men in order that the well structure might be supported and positioned by one man while the actual fastening operation was performed by the other man.

In view of the foregoing it is the primary object of this invention to simplify the installation of window wall structures, and a related object is to enable such mounting to be accomplished quickly and easily by one workman.

Another important object of the invention is to provide a well-type basement window structure wherein the window frame and well structure embodies inter-related mounting and connecting means whereby the well member may be quickly and easily put in place across the window opening after the frame has been put in place as by casting in a basement wall. More specific objects are to embody fastening elements in the jambs of such a window frame in positions such that the frame may be mounted in the concrete forms, and in such a way that such fastening elements are subsequently exposed and may function in securing the well member in place.

Other and further objects of the present invention will be apparent from the following description and claims, and are illustrated in the accompanying drawings, which, by way of illustration, show a preferred embodiment of the present invention and the principles thereof, and what is now considered to be the best mode in which to apply these principles. Other embodiments of the invention embodying the same or equivalent principles may be used and structural changes may be made as desired by those skilled in the art without departing from the invention.

In the drawings:

FIGURE 1 is a fragmentary perspectives view of a well-type basement window structure embodying the features of the invention;

FIGURE 2 is a vertical sectional view taken through the window frame while it is in position in the concrete forms that define the basement wall;

FIGURE 3 is a horizontal sectional view taken substantially along the line 3—3 of FIGURE 2 and showing the jamb of the window frame and the associated securing element in the positions that are initially occupied in the forms;

FIGURE 4 is a view similar to FIGURE 3 after removal of the forms and after the well has been mounted in position on the securing elements; and

FIGURE 5 is a schematic view illustrating a window frame and three well members disposed at three different levels so as to illustrate the adaptability of the present invention to different conditions encountered on the job.

2

For purposes of disclosure the invention is herein illustrated as embodied in a well-type basement window installation 10 in which a metal window frame 11 is cast in place in a concrete basement wall W, and with an arcuate 5 corrugated sheet metal well 13 spanning the window opening and secured in position along the opposite outside vertical edges of the window frame 11 in such a way that the well 13 may be readily and easily secured in position by but one workman at any one of a plurality of levels 10 according to the proposed outside grade level.

The window frame 11 in the present instance is of the wide or full wall-width type so that it completely spans the space between the inner and outer forms 14 and 15, as shown in FIGURE 2, thus to eliminate the need for 15 special window-forms for defining parts of the window opening. This full width of the form of the frame 11 is desirable and convenient, but it is not absolutely essential to the present invention, because, as will become apparent, the cooperation between the frame 11 and the well 13 is accomplished at the outer vertical edges of the frame 11.

Thus, the window frame 11 is formed from sheet metal to provide a head 11H and a sill 11S that are connected by vertical jambs 11J and these members have appropriate shoulders formed on their inside surfaces to cooperate 25 with a window sash 17 and a screen or other supplemental sash 18. The particular form and arrangements of the sash elements is immaterial insofar as the present invention may be concerned.

Under the present invention, the outer edges of the 30 jambs 11J have outwardly directed flanges 11F, and the other edges of the frame elements may be similarly flanged at 11E if desired. The flanges 11F at the inner and outer edges of the jambs 11J are utilized in the present instance in supporting the frame 11 in position in the 35 forms, and as shown in FIGURE 1 of the drawings, openings 19 are provided in the outer and inner flanges of the jamb to receive fastening elements such as nails for locating and supporting the frame in the forms during the pouring operation.

40 The well members 13, as herein shown, are made from corrugated sheet metal so as to have an arcuate form when viewed in plan, and the opposite ends of the wall members have flat coplanar flanges 13F formed thereon for use in the mounting and supporting of the well 13 in its position of use.

Under the present invention, the supporting or mounting of the well in its position of use is accomplished by cooperation of means that are provided respectively on the outer flanges 11F of the jamb and on the flanges 13F 50 of the well members. Such mounting and securing means, under the present invention, are so formed and arranged that the securing or mounting means do not in any way interfere with the mounting of the window frame in the forms, and yet such means are readily operated after the 55 forms have been removed to enable the well members 13 to be put in place across the outer face of the window opening.

Thus, such cooperating means as herein shown, comprise slots in one of the members and cooperating threaded devices carried by the other member, in the specific form shown, the means that are associated with the window frame 11 are provided by a plurality of screws 20 or studs that are inserted at vertically spaced points through the outer flange 11S of each jamb and such 60 mounting is accomplished in a way that in effect recesses the heads 20H of the screws into the outer faces of the flanges 11F so that these heads do not interfere with the mounting of the window frame 11 in the concrete forms. Thus, the flange 11F at each point where a screw 20 is 65 to be mounted is perforated and recessed inwardly as at 20R, FIGURES 3 and 4. The screws 20 are preferably 70

of the self-threading type usually used with sheet metal, and in the initial assembly of the frame 11, the screws are inserted into the flange 11F so that the heads 20H of the screws are located completely within the recess 20R, as shown in FIGURE 3. With this arrangement, the flange 11F may abut the adjacent surface of the outer form 15 as shown in FIGURE 3. If a narrow type window frame is used, the space between the frame and the inner form 14 may be filled by the usual filler or brick. After the frame 11 has been thus mounted in the forms, the wall W is poured, and it should be noted that the screws 20 are preferably coated with a parting substance such as grease so that after the concrete has hardened the screws 20 may be backed partially out of the concrete to a point where the heads 20H of the screws extend outwardly from the outer surface of the wall W.

When the forms have been removed and the screws 20 have been backed out of their openings for a short distance, the workman may readily and easily mount the well members 13 in position on the well, and to facilitate this, the flanges 13F of the well members have a plurality of vertically-spaced inverted keyhole slots 22 formed therein. It will be noted that adjacent screws 20 are equally spaced from each other and that the vertical spacing between the slots 22 is, in each instance, equal to one-half of the vertical spacing between the mounting screws 20. This provides for association of the well members 13 with the mounting screws 20 at any one of a plurality of different levels as determined by the proposed outside grade level that is to be established about the building.

When the screws 20 have been backed out, a single workman may lift the well member 13 and may engage the selected keyhole slots 22 with the screws 20, the heads 20H passing through the enlarged lower ends of the keyhole slots and when this has been done, the well is lowered slightly so that the heads 20H are disposed opposite the narrow upper ends of the slots 22. The workman may then tighten the screws as shown in FIGURE 4 of the drawings so that the well is held securely in position and tightly against the outer flange 11F of the jamb of the window frame.

From the foregoing description it will be apparent that the present invention materially simplifies and reduces the cost of installing well-type basement window assemblies, and particularly, it will be evident that the present invention so simplifies the association of the well member with the wall that the mounting operations may be performed by a single workman and this may be done quite rapidly and reasonably.

Thus while we have illustrated and described a preferred embodiment of our invention it is to be understood that changes and variations may be made by those skilled in the art without departing from the spirit and scope of the appended claims.

We claim:

1. A basement window adapted to be cast in place in a concrete wall of a predetermined thickness and which may serve as a form for the window opening as the wall is cast, said window comprising a sheet metal frame having a thickness from its inner side to its outer side

equal to said predetermined thickness of the wall in which the frame is to be cast, said frame having a pair of substantially vertical flanges extending away from each other along the outer vertical sides of the frame, said flanges each having a plurality of inward recesses with central openings therein formed in said vertical flanges at vertically spaced points, locking screws threaded through said openings and having heads disposed within the respective recesses flush with the outer surfaces of said vertical flanges so that said flanges may receive a form in flush engagement therewith, said screws being retractable from the flush positions thereof for use in locking a well member to the window frame.

2. A basement window adapted to be cast in place in a concrete wall of predetermined thickness and which may serve as a form for the window opening as the wall is cast, said window comprising a sheet metal frame having a thickness from its inner side to its outer side equal to said predetermined wall thickness, said frame having a pair of vertical flanges along opposite ends of its outer side and extending in opposite directions away from each other, each of the said flanges having three vertically spaced recesses formed therein, and said recesses having central openings therethrough, said flanges each having three screws threadably engaged in the openings along each flange, the screws having heads disposed in said recesses flush with the outer surface of the outer flanges for flush engagement of forms with said window frames, a parting compound on the threads of the screws providing free turning of the screws in a concrete encasing the window frame, the screws retractable from the flush position in the outer flange to lock a well member to said window frame in a selected vertical position.

3. A window structure comprising a basement window having a frame, said frame having a pair of substantially vertical outer flanges extending outwardly from said frame, a well member having a plurality of locking slots equidistantly spaced along opposite edges of said well member, a plurality of screws threadably mounted in the outer flanges, said screws having a distance between centers of adjacent screws in an even multiple of the distance between centers of adjacent slots in the well member, said screws positioned within mating slots locking the well member to the frame in a selected vertical position, said screws having heads retractably flush with the outer surface of the flange to provide a flush surface for engaging a concrete form to encase and position the frame in concrete, and a parting compound on the threads of said screws providing free turning of the screws in a concrete encasing the window frame.
